[57] CLAIM

The ornamental design for a finger watch, as shown and described.

DESCRIPTION

FIG. 1 is a perspective view of a finger watch showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 a perspective view of a finger watch showing my first alternate design;

FIG. 9 is a top plan view of the first alternate design depicted in FIG. 8;

FIG. 10 is a bottom plan view of the first alternate design depicted in FIG. 8;

FIG. 11 is a front elevational view of the first alternate design depicted in FIG. 8;

FIG. 12 is a rear elevational view of the first alternate design depicted in FIG. 8;

FIG. 13 is a left side elevational view of the first alternate design depicted in FIG. 8; and,

FIG. 14 is a right side elevational view of the first alternate design depicted in FIG. 8.

The broken-line showings of a hand in FIGS. 1 and 8 are environmental only and form no part of the claimed design.
